Des. 211,813
Patented July 30, 1968

211,813

CLOCK FACE

Marion K. Summers, W. Commerce St.,
Brownstown, Ind. 47220

Filed June 2, 1966, Ser. No. 2,510

Term of patent 14 years

(Cl. D42—7)

FIG. 1.

FIG. 2.

FIG. 1 is a front elevational view of a clock face showing my new design; and

FIG. 2 is a bottom plan view thereof.

The essential features of my design reside substantially in the full line disclosure on the drawing; more particularly in the lined pattern connecting coins or tokens which serve, together with conventionalized pips, as representations of the hourly intervals on the clock face.

I claim:

The ornamental design for a clock face, substantially as shown and described.
